UNITED STATES PATENT OFFICE.

JOHN W. ANDERSON, OF GARY, INDIANA.

INDICATING DEVICE.

Application filed March 28, 1927. Serial No. 178,991.

My invention relates to indicating devices and particularly to indicating devices of the type shown and described in my copending application, Serial No. 111,345, filed May 24, 5 1926.

One form of the present invention is particularly adapted to be used in connection with the cooling system of an internal combustion engine and will produce a signal 10 warning in advance of imminent wastage of cooling liquid because of overheating, another and different signal warning when such wastage is in progress, and still another and different signal warning when such or other 15 wastage has reduced the supply of cooling liquid to a predetermined level in its container, and a different signal when no wastage of cooling liquid through overheating is imminent or in process.

20 The invention has among its other objects the production of a device of the kind described so constructed that it may be quickly and easily attached to or detached from the filling tube of an automobile radiator without injury to the overflow pipe.

A particular object of the invention is to provide improved construction for devices of the kind described so that they may be produced in commercial quantities at a relatively 30 low cost.

Another particular object of the invention is to provide improved construction for devices of the kind described, which construction insures that the signals given by the 35 devices will invariably be noted by the drivers of the vehicles to which the devices are attached.

Many other objects and advantages of the construction herein shown and described will 40 be obvious to those skilled in the art from the disclosure herein given.

To this end my invention consists in the novel construction, arrangement and combination of parts herein shown and described, 45 and more particularly pointed out in the claims.

In the drawings, wherein like reference characters indicate like or corresponding parts:

50 Fig. 1 is a vertical central section taken through a device embodying the invention, the device being shown in connection with the filling tube of an automobile radiator;

Fig. 2 is a section taken on line 2—2 of 55 Fig. 1;

Fig. 3 is a section taken on line 3—3 of Fig. 1; and

Fig. 4 is a vertical section taken through a device embodying another form of the invention.

Referring for the present to Figs. 1 to 3, inclusive, the reference character 10 designates generally a radiator of the type commonly employed in automobiles, or the like, only a portion of the radiator being shown as 60 the invention does not relate to the construction thereof. The radiator 10 is provided with the usual filling tube 12 and with the usual overflow tube 14, the construction being such, in this instance, that the upper end of 70 the overflow tube projects up into the filling tube 12 and is disposed substantially centrally thereof. The upper end of the filling tube 12 is normally closed by a cap 15 which is preferably screw-threaded upon the filling 75 tube 12. Screw-threaded into the cap 15 and projecting downward therefrom is a tubular member 17 extending down into the radiator 10 to a point below the normal maximum liquid level therein which may be said to be 80 approximately coincident with the lower end of the overflow tube 14. In the preferred embodiment of the invention, the tubular member 17 preferably projects into the radiator to a point approximately coincident with the 85 normal minimum liquid level therein, the normal minimum liquid level being the level at which there is sufficient liquid in the cooling system to permit the internal combustion engine of the automobile to function efficiently although a less amount of liquid will permit the engine to heat up to an undesirable 90 temperature. However, in some instances, I may prefer to have the tubular member 17 terminate a relatively short distance below the normal maximum liquid level in the 95 radiator or I may prefer to omit the tubular member entirely as hereinafter explained. As best shown in Fig. 1, a nut 19 is preferably provided upon the tubular member 17 for locking it against accidental displacement relative to the cap 15.

Formed in the cap 15 is a central opening 21 which, at its lower end, is preferably enlarged as at 22 to provide a shoulder 23 and projecting through the opening 21 is a dome or hollow member 24 which is preferably formed of glass, or the equivalent, the member 24 having its lower end open so that fluid may pass from the tubular member 17 into 100 110

the member 24 through apertures 25 provided in a disc 25^c. The hollow member 24 is provided with an outwardly extending annular flange 26 which projects into the annular portion 22 of the opening 21, the construction being such that the tubular member 17 cooperates with the disc 25^c and a packing ring 27 to clamp the flange 26 to the cap 15. It is readily understood that the disc 25^c serves as a baffle and retards the flow of vapor and liquid from the radiator into the hollow member 24. This reduces wastage of the cooling liquid through the overflow tube.

Projecting through a central aperture 28 provided in the disc 25^c is a tube 29 which preferably extends from a point adjacent the upper end of the hollow member 24 to a point below the disc 25^c, the tube 29 being preferably provided with an outwardly extending annular bead 30 intermediate its ends to prevent it from being forced an undesirable distance up into the hollow member. If desired, the bead 30 may be soldered to the disc 25^c as indicated at 32. The lower end of the tube 29 is preferably flared as at 34 to receive a frustro-conical end 35 provided upon a funnel-shaped member 36 which is also preferably provided with an outwardly extending annular bead 37. The annular bead 37 seats in an annular groove 39 provided in the tubular member 17, the construction being such that the funnel-shaped member 36 is held against longitudinal displacement relative to the tubular member 17. It will be noted that the overflow tube 14 projects up into and seats in the frustro-conical end 35 of the funnel-shaped member 36. Formed in the frustro-conical end 35 below the upper end of the overflow tube 14 are apertures 40 through which fluid may pass from the interior of the radiator 10 up into the hollow member 24. The funnel-shaped member 36 also serves as a baffle and reduces wastage of the cooling liquid through the overflow tube. It may be mentioned at this point in the description that the lower end of the overflow tube 14 communicates with the atmosphere so that fluid may pass from the radiator into the hollow member 24 and then be discharged from the cooling system through the overflow tube 14.

It is readily understood that the cap 15, the member 24, the funnel-shaped member 36 and the tube 29 may be removed as a unit from the filling tube 12 when the supply of cooling liquid in the radiator is to be replenished. Then after the supply of cooling liquid has been replenished, the cap may be screw-threaded again upon the filling tube and the frustro-conical end 35 of the funnel-shaped member 36 will seat upon the upper end of the overflow tube 14. It will be noted that an aperture or vent 42 is provided in the wall of the tubular member 17. The purpose of this construction will presently appear.

The operation of the apparatus shown in

Figs. 1 to 3, inclusive, resembles the operation of the apparatus shown in the aforementioned copending application and is substantially as follows: assuming that the automobile upon which the apparatus shown in Figs. 1 to 3, inclusive, is mounted is in operation and that it is operating in such manner that the temperature of the cooling fluid does not approach the boiling point, there will be substantially no indication of any kind in the glass member 24. However, if for any reason, the temperature of the cooling fluid approaches its boiling point, a solid column of water will appear in the glass member 24, it being assumed that the tubular member 17 projects below the liquid level in the radiator. The column of water extending into the glass member 24 rises and falls irregularly and at times may disappear from the glass until the cooling fluid boils with sufficient violence to create a relatively high pressure within the radiator. Then a steady flow of liquid through the glass member 24 will be observed, this liquid being discharged from the cooling system through the tube 29 and the overflow tube 14 which communicates preferably directly with the atmosphere. If the driver of the automobile heeds the warning and slows down or stops the engine or corrects any other condition which may be causing the abnormal condition within the radiator, the boiling ceases and the cooling fluid ceases to waste through the overflow tube 14. It may be mentioned that as long as the tubular member 17 extends below the liquid level in the radiator and the overflow tube 14, the water glass shows plainly a steady flow of cooling fluid in appreciable amount of bubbles or irregularities of any kind.

If the driver does not heed this warning and the operation of the engine is continued without modification, the cooling liquid wastes through the overflow tube 14 until the liquid level in the radiator falls below the lower end of the tubular member 17 whereupon steam or a mixture of steam and liquid wastes through the tube 29 and the overflow tube 14, the violent churning liquid and steam being readily observable in the glass 24 instead of the aforementioned column of liquid. This churning continues as long as there is any liquid left in the radiator or until the boiling and steaming ceases.

Like the operation of the apparatus described in the aforementioned application, the apparatus shown in Figs. 1 to 3, inclusive, of this application may be said to give four distinct signals which indicate, respectively, four distinct stages in the condition of the cooling system when the temperature of the liquid therein is increased and the liquid is wasted to such an extent that any further waste thereof will be accompanied by serious damage to the engine by overheating. Briefly, the stages are as follows:

The first stage: from atmospheric temperature to normal operating temperature. During this stage, the cooling liquid does not reach the boiling point and does not waste and therefore, the glass member 24 remains clear. This signifies that the operating conditions are normal in so far as any special attention of the operator is required.

The second stage: from normal operating temperature to simmering temperature and a substantially unbroken column will then appear in the glass member 24, the height of the column fluctuating in the manner described above.

The third stage: from simmering temperature creating comparatively slight pressure to active boiling which causes wastage of cooling fluid because of the comparatively high pressure produced in the radiator. The glass member 24 then becomes completely filled with an unbroken column of liquid flowing therethrough and wasting through the overflow tube 14.

The fourth stage: from active boiling and wasting of a still adequate supply of cooling liquid to a comparatively overheated steaming and wasting of a boiling liquid. After sufficient cooling liquid has wasted through the overflow tube 14 to bring the liquid level within the radiator below the lower end of the tubular member 17, the glass member 24 shows violently churning steam and water passing therethrough. This signal is readily distinguished from the other three described and indicates that the cause of overheating has not been corrected. This fourth signal will be given independently of any other signal whenever the level of the cooling liquid is below the bottom end of the tubular member 17. For instance, if due to a leak in the radiator a supply of cooling liquid adequate at the beginning of the trip is reduced and while conditions remain normal and no boiling occurs sometime after the level of that supply falls below the bottom end of the tubular member 17, boiling of the cooling liquid will occur and the 4th warning signal will be given to the operator.

Since exhaustion of its reserve supply of cooling liquid must precede any serious damage to the automobile from overheating, separate easily differentiated and highly visible signals or indications relative to the above described stages are given and are obviously more useful than the mere indication of temperature which may have no fixed relation to the point of actual boiling and wasting of the cooling fluid.

As pointed out above, the disc 25^a and the funnel shaped member 36 not only position the tube 29 and cooperate with the overflow tube 14, respectively, but also tend to retard the flow of water through the tubular member 17. This is advantageous in that as long as the operator is given a signal that liquid

is being wasted from the cooling system, it is not necessary to discharge a relatively large amount of liquid therefrom. Obviously, the supply of cooling liquid is conserved.

The aforementioned aperture or vent 42^a provided in the tubular member 17 insures that siphonic action will not set up through the tubular member 17, the glass member 24 and the overflow tube 14.

As set forth above, it may be advisable in some instances, to dispense with the tubular member 17 and the funnel-shaped member 36. In that event, the tube 29 may be soldered to the washer 26^a in such manner that the upper end of the overflow tube 14 will seat in the flared end 34 thereof. The above described signals will then appear in the glass member 24 in a manner resembling that in which they appear when the tubular member and the hollow-shaped member are employed, but of course, the churning signal will appear much earlier during the wasting of the cooling liquid. If the liquid level in the radiator 10 is relatively low, it will probably happen that no column of liquid will pass through the glass member 24 but that the initial signal of abnormal conditions will be a flow of steam through the glass member. Of course, if the conditions of operations are not corrected this signal will be followed immediately by the churning signal.

Referring to Fig. 4, wherein I have shown another form of the invention embodied in a device which resembles the device shown in Figs. 1 to 3, inclusive, the reference character 10^a designates a radiator which may be substantially identical with the aforementioned radiator 10 and preferably comprises a filling tube 12^a which is substantially identical with the aforementioned filling tube 12. A cap 15^a screw-threaded upon the upper end of the filling tube 12^a is provided with a central aperture 21^a which is enlarged at its upper end as indicated at 45 to accommodate an apertured disc 25^a, a packing ring 27^a and an annular flange 26^a, the annular flange 26^a being formed integral with a hollow member 24^a which is preferably made of glass or some other transparent material. Secured to the cap 15^a by one or more screws 47, or the equivalent, is an arcuate plate 48 which holds the flange 26^a against the packing ring 27^a and holds the packing ring and the disc 25^a in place in the enlarged portion 45 of the aperture 21^a. Screw-threaded into the cap 15^a and projecting downward therefrom is a tubular member 17^a which is locked by a nut 19^a against accidental displacement relative to the cap. A tube 29^a which projects through a central aperture 28^a provided in the disc 25^a has its lower end flared as at 34^a to receive a frusto-conical end 35^a provided upon a funnel-shaped member 36^a. The tube 29^a is preferably provided with an annular bead 30^a which prevents the tube 29^a

from being forced an undesirable distance up into the glass member 24^a. The funnel-shaped member 36^a is preferably provided with an outwardly extending annular bead 37^a which engages an annular groove 39^a provided in the tubular member 17^a, the construction being such that the tube 29^a and the funnel-shaped member 36^a are held in place within the tubular member 17^a. The radiator 10^a is provided with an overflow tube 14^a, the upper end of which is centrally disposed in the filling tube 12^a and is adapted to seat in the frusto-conical end 35^a of the funnel-shaped member 36^a.

15 Obviously, the operation of the device shown in Fig. 4 is substantially identical with the operation of the device shown in Figs. 1 to 3, inclusive. But in the device shown in Fig. 4, the glass member 24^a may be quickly 20 and easily replaced if the arcuate plate 48 is first removed from the cap 15^a. In the device illustrated in Figs. 1 to 3, inclusive, the tubular member 17 must be removed from the cap 15 before the glass member 24 can be replaced.

Having thus described my invention, it is obvious that various immaterial modifications may be made in the same without departing from the spirit of my invention; hence I do 30 not wish to be understood as limiting myself to the exact form, construction, arrangement and combination of parts herein shown and described, or uses mentioned.

What I claim as new and desire to secure by 35 Letters Patent is:

1. The combination with an automobile radiator having a filling opening, and an overflow tube, the upper end of the overflow tube being centrally disposed in said filling 40 opening, a cap for said filling opening, a transparent hollow member carried by said cap and concentrically disposed with said upper end of said overflow tube, said hollow member communicating with the interior of 45 said radiator, means for retarding the flow of fluid into said hollow member, and tubular means projecting into said hollow member and communicating with said overflow tube, said tubular means being carried by said cap.
- 50 2. An indicating device of the kind described comprising a closure member for the filling opening of an automobile radiator provided with an overflow pipe having its upper end centrally positioned in said opening, a substantially transparent hollow member 55 centrally positioned in said closure member and projecting thereabove, said hollow member being apertured at its lower end, a tube centrally positioned in said closure member 60 and projecting up into said transparent hollow member, the tube having an opening at its upper end whereby it communicates with the interior of the hollow member and the lower end of the tube being adapted to 65 substantially close the upper end of the over-

flow pipe against direct communication with the interior of the radiator, and tubular means extending downwardly from the lower end of said transparent hollow member and encircling said tube, said tubular means extending below the upper end of the overflow pipe and the internal diameter thereof being larger than the external diameters of the tube and the pipe.

3. An indicating device of the kind described comprising a closure member for the filling opening of an automobile radiator provided with an overflow pipe having its upper end centrally positioned in said opening, a substantially transparent hollow member centrally positioned in said closure member and projecting thereabove, said hollow member being apertured at its lower end, a tube centrally positioned in said closure member and projecting up into said transparent hollow member, the tube having an opening at its upper end whereby it communicates with the interior of the hollow member and the lower end of the tube being adapted to substantially close the upper end of the overflow pipe against direct communication with the interior of the radiator, and tubular means extending downwardly from the lower end of said transparent hollow member and encircling the tube, said tubular means extending below the normal maximum water level in the radiator and the internal diameter thereof being larger than the external diameter of the tube and the pipe.

4. The combination with an automobile radiator having a filling opening, and an overflow tube, a transparent member communicating with said opening and said overflow tube so that vapor and liquid may be discharged from said radiator through said transparent member into said overflow tube, and means functioning as a baffle to retard the flow of vapor and liquid from said radiator into said transparent member.

5. An indicating device of the kind described comprising an apertured closure member for the filling opening of an automobile radiator provided with an overflow pipe, a substantially transparent hollow member mounted on said closure member and arranged to communicate with the interior of said radiator, and means including tubular means provided with a flaring mouth adapted to seat upon the upper edge of said overflow pipe for operatively connecting said hollow member to said overflow pipe so that vapor or liquid passing into said hollow member from the interior of said radiator may be discharged through said overflow pipe.

6. An indicating device of the kind described comprising an apertured closure member for the filling opening of an automobile radiator provided with an overflow

pipe, a substantially transparent hollow member mounted on said closure member and arranged to communicate with the interior of said radiator, means whereby said hollow member may discharge liquid into said overflow pipe, and a plurality of spaced means for retarding the flow of vapor and liquid into said hollow member from said radiator.

7. The combination with an automobile radiator having a filling opening and an overflow tube, the upper end of the overflow tube being aligned with said filling opening, a closure member for said filling opening, a transparent hollow member carried by said closure member and communicating therethrough with the interior of said radiator, tubular means projecting through the closure member and adapted to be removed from the radiator as a unit with the closure member, said tubular means projecting into said hollow member and communicating with said overflow tube, and means disposed at the lower end of said tubular means and constituting a baffle for retarding the flow of fluid from said radiator into said hollow member.

8. In combination with an automobile radiator having a filling opening and an overflow tube, the upper end of said overflow

30 tube being centrally disposed in said filling opening, a cap for said filling opening, a hollow transparent member carried by said cap, tubular means communicating with said transparent member and extending into said radiator below the normal liquid level thereof, and tubular means projecting through the cap whereby said transparent member communicates with said overflow tube, said last named tubular means being carried by said cap.

35 40 45 50 55 9. In combination with an automobile radiator having a filling opening and an overflow tube, the upper end of the overflow tube being centrally disposed in said filling opening, a cap for said filling opening, a transparent hollow member carried by said cap, tubular means communicating with said transparent member and extending into said radiator below the normal liquid level thereof, and tubular means communicating with the upper end of said overflow tube and with the interior of said transparent member, said last named tubular means being carried by said cap.

In testimony whereof, I have hereunto signed my name.

JOHN W. ANDERSON.
